COMBINED SWITCH AND CIRCUIT BREAKER

Walter S. Mayer, Philadelphia, Pa.

Application May 31, 1932, Serial No. 614,499

8 Claims. (Cl. 200—88)

My invention relates to electrical switches of the automatic type and for use with either direct or alternating current.

An object of the invention is to provide an electrical switch or circuit breaker which shall be simple in construction, capable of preventing the operator from fully closing or holding the switch closed during the existence or continuance of a predetermined electrical condition in a circuit, and one that is fully enclosed by an insulated casing, so that the operator can not touch the live parts while in circuit.

Another object of my invention is to provide automatic delayed time actuation of the device on small abnormal circuit conditions, in combination with automatic instantaneous actuation on short circuit conditions, or large abnormal circuit conditions.

A further object of my invention is to provide a device which has electrodes or terminals of the knife blade, or ferrule types, or equivalent, that can be inserted in standard National Electric Code fuse clips or the like, similar to the commercial fuse, and having combinations of construction which permit the device being made in such sizes that its lengths may be made to correspond to the lengths of the various N. N. Code fuses. Hence my device is removably interchangeable with the commercial fuse.

30 The arrangement of my terminals also permit lugs being attached thereto, so that line wire connections can be made, when it is desired not to insert the device in fuse clips, as for instance when it is permanently secured to a panel or the like, and securing means thereof, is provided as herein fully described.

Another object of my invention, is to provide a combined switch and circuit breaker having a rectilinearly reciprocable symmetrical switch element which operatively bridges the contacts of terminals adapted to engage fuse clips or the like, all in substantially vertical alignment, and which switch element moves substantially transversely or at right angles to said alignment, and the switch element in the open position to be entirely disconnected electrically from the terminals, so as to give a double break, and thus permit circuit connections without regard to line or load side of the circuit.

55 My device is symmetrical, reversible, interchangeable, and operable in any position. The unique combination of the switch element of my device, permits laminated contacts with auxiliary carbon shunts to be used, and hence the resilient

contact pressure thereof, assists to open the breaker under predetermined conditions.

Another object of my invention is to provide contacts which form a loop or coil and envelop the core of a U shaped high permeable member 60 to produce a magnetic blow out for extinguishing the arc, incident upon opening the circuit under circuit conditions, by diverting the arc flashes laterally outward through the relief apertures in the walls of the casing.

Another object of my invention is to utilize the induced magnetic action by the bridge element, in the uprights which guide said bridge element and support the operating mechanism, for attracting an armature on heavy abnormal circuit conditions, to trip the trigger or the like, and allow the bridge element to open the electrical circuit. The uprights and outer bearing pillar and collar, being made of steel, form a U shape magnet, by reason of the bridge element 75 passing thru the inside thereof, and there is enough magnetism induced therein on heavy abnormal circuit conditions to attract the armature for the aforesaid reasons. Thus, it is not necessary to provide an auxiliary solenoid for this 80 purpose.

Another object of my invention is to provide a gripping means for withdrawing the device, as a whole, from the fuse clips which they engage.

A further object is to provide manual as well 85 as selective time automatic means for opening the circuit breaker, and also means for effecting a quick manual as well as automatic, breaking action.

In my Patent No. 1,188,966, dated June 27, 90 1916, the bridging member is tubular shaped, making a frictional wiping contact with the terminal contacts, and moves longitudinally with the alignment. The aforesaid friction retards the operation, and the general combination does 95 not permit blow outs, selective time operation, quick manual operation, nor high current carrying capacity, and no means are provided for line connections when not engaged with the fuse clips. There is also the absence of arcing shunts to prevent 100 burning of the contacting surfaces, or to prevent the freezing of the contacting surfaces together, so to speak, and also the combination and construction shown in the aforesaid patent is congested and inaccessible. All of these objections and difficulties are overcome in my new 105 invention herein submitted.

My present invention consists of certain novel features of construction, as will be more fully described, and pointed out in the detailed de- 110

scription, the drawings, and the appended claims.

Referring to the drawings:

Fig. I shows a vertical sectional view of my improved circuit breaker taken on the line I—I of Fig. II.

Fig. II is a sectional view taken on the line II—II of Fig. I with the cover component of the casing of the circuit breaker removed.

Fig. III is a sectional view taken on the line III—III of Fig. I.

Fig. IV is a fragmentary detail sectional view taken on the line IV—IV of Fig. I.

Fig. V shows the bottom end view of the circuit breaker.

Fig. VI is a cross sectional view taken on the line VI—VI of Fig. I.

Fig. VII is a fragmentary view corresponding to Fig. V, and illustrating an important feature of my invention.

Fig. VIII is a detail sectional view taken as indicated by the arrows VIII—VIII in Fig. VII.

Fig. IX is a perspective view of one of the bridge guiding members embodied in the circuit breaker.

Fig. X is a perspective view of the carriage of the contact bridging element of the circuit breaker.

Fig. XI is a perspective view of the slide which carries the latch member by which the bridge element is normally held in closed position.

Fig. XII is a perspective view of the latch member.

Fig. XIII is a perspective view of a thermic element which is relied upon to trip the circuit breaker under small abnormal circuit conditions.

Fig. XIV is a fragmentary detail view showing a modified form of means for operating the circuit breaker manually.

Fig. XV is a sectional view similar to Fig. I except that a "triple toggle latching" mechanism is substituted instead of the "trigger latching" mechanism as further described.

Fig. XVI is a view of Fig. XV taken as in Fig. III except the armature is not shown.

Fig. XVII is an end view of Fig. XV showing the ferrule terminal.

Fig. XVIII is a similar view with the terminal lug 134 attached inside the counterbored cylindrical terminal.

Fig. XIX is a section of Fig. XVIII showing the line wires attached to the lug 134.

With more specific reference first to Figs. I, II, III, V, and VI, my improved circuit breaker comprises a vertically-elongated longitudinally-split box-like casing 15 which is preferably of molded dielectric composition and which encloses the working parts later on individually referred to. As shown a base component 16 and a cover component 17 of the casing meet in a rabbetted juncture 18 whereby the two are held in perfect alignment and registry. The cover component 17 is removably secured by screws 19 which pass through the openings in its side walls into internally-threaded metallic bushings 20 embedded in the side walls of the base component 16, see Fig. VI. Lodged within recesses 22 and 23 externally of the upper and lower end of the base component 16 are copper terminals 24 and 25 which are respectively formed with knife blade projections 26 and 27 capable of engagement with fuse clips or the like on a switch or instrument panel. With the provisions above described, my breaker may obviously be used in place of an ordinary cartridge fuse. To facilitate application and removal of the breaker when the

latter is used in place of a fuse as explained, I have provided the cover component 17 of its casing at its front with an integrally formed grasp projection 21.

To enable line wires if desired, to be connected, the knife blade ends 26, 27 of the terminals 24, 25 are pierced as at 29 to take clamp bolts, such as are exemplified at 30 in Figs. VII and VIII, for securing the lugs 30a into which the line wires are attached. In the previous described use of the circuit breaker, the base component 16 of the casing 15 is secured to the switch board or panel by means of screws or bolts and counterbored holes are provided for the passage of the screws or bolts in its side walls as shown at 31 in Fig. II.

In Fig. I it will be observed that the terminals 24, 25 are secured by screw bolts 32, and 33, 34 respectively, which bolts extend through openings in the inset portions of the back wall of the base component 16 to the interior of the casing 15 where they are respectively fitted with clamp nuts 35, and 36, 37. Overlaid upon the angle of the recessed upper and lower portions of the back wall of the base component 16 of the casing 15, are correspondingly configured contact pieces 38 and 39 which have their horizontal extremities pierced for passage of the securing screw bolts 32, 33, 34 respectively. The vertical extremities of these contact pieces 38 and 39 provide abutment faces for the bridging element 40 of the circuit breaker, and as shown, are retroverted at 41 and 42 to respectively embrace the transverse or core portions of the U shaped blow-out magnets 43, 44. The parallel sides 43a and 44a of each of the blow-out magnets 43 and 44, respectively, extend in the direction of the movement of the bridging element. The blow-out magnets 43 and 44 are secured, with interposition of the U shaped shields 45, 46 of insulating material, to contact pieces 38 and 39. The purpose of the shields 45 and 46 is to protect the magnets 43 and 44 from the effects of the arc which is attendant upon either the manual or the automatic opening of the circuit breaker; while said magnets serve to divert the arc flashes laterally outwardly of the casing 15 through the relief apertures 47, 48 at the upper and lower ends of the cover component 17. The bridging element 40 comprises an open slide non-magnetic member 49 fashioned from sheet copper, see Fig. X, with spaced side portions 50, 51 and connecting top and bottom transverse bars 52, 53, which latter are apertured as at 54, 55 for the passage of rivets whereby the laminated contact brushes 56, 57, as well as the spring arms 58, 59 for the arc-taking carbon blocks 60, 61, are secured to said slide member. The side portions 50 and 51 of the slide member 49 are formed with outwardly bent lugs 62, 63 for engaging longitudinal slots 64 of a pair of bracket-like guides 65, 66 whereof but one bracket-like guide is illustrated in perspective in Fig. IX.

These guides 65, 66 are constructed from sheet iron or other magnetic material, and as shown in Figs. I and III, are secured in spaced relation within the central hollow 67 of the casing 15, by means of screws 68, 69 which pass through the back wall of the base component 16 and through the flanges 70, 71 of each of the guides. It will be further noted in Figs. I and III that the guides 65, 66 extend forwardly into the cover component of the casing 15 and that they are connected together, at their front ends, by a cross pin 72 that is, also, comprised of magnetic material. Extending transversely between the side portions of 150

the slide member 49 is a pin 73 of non-magnetic material. Rollers 74 and a central spacing sleeve 75 are mounted upon the pin 73. Between the sleeve 75 and the spacing sleeve 76 on the cross pin 73 connecting the guides 65, 66, extends a tension spring 77 that tends to draw the bridging element 40 away from the contacts 38 and 39.

The means provided for normally holding the bridging member 40 in closed circuit position in opposition to the spring 77 has the form of a trigger latch 78 which is illustrated in perspective in Fig. XII. As shown, the trigger latch embodies a pair of spaced metallic side pieces 79, 79A with hooks 80 at one end and tails 81 at the other end that are joined by a cross connecting piece 82 of insulation formed with a rounded traverse rib 83. The side pieces of the trigger latch 78 are further formed with arcuate arms 84 that extend close to and in the same plane as the hooks 80 and the arms are pierced as at 85 for pivotal mounting of the trigger latch 78 on a non-magnetic cross pin 86 carried by a non-magnetic slide block 87 which slide block is shown in Fig. XI. The slide block 87 has its ends squared to non-rotatably engage the slots 64 of the guides 65, 66 and the slide block is to the rear of the slide 49 of the bridging element 40. The recessed portion of the slide block limits the movement of the trigger 78.

The two guides 65, 66, in conjunction with the pin 72 and collar 76 that connect their upper ends, constitute a U shaped magnet by reason of the bridging element 40 passing thru the inside thereof, and in the event of sudden and excessive abnormal circuit condition of the circuit in which the breaker is connected, attracts the iron armature 88.

As shown this armature 88 is riveted to a brass saddle 89 which is pivotally mounted about a non-magnetic pin 90 extending through the guides 65, 66 adjacent the flanged ends of the latter.

Normally the armature 88 is maintained retracted away from the guides 65, 66 by means of springs 91, 91a, shown in Figs. I and III. As the armature is attracted under the conditions referred to, it strikes the curved extremities 84 of the trigger latch 78 whereby the latter is swung clockwise in Fig. I and its hook extremities 80 disengaged from the rollers 74 that are mounted on the cross pin 73 of the slide 49. As a consequence, the bridging element 40 is rapidly withdrawn by the spring 77 to an open circuit position away from the contacts 38, 39. Incident to the foregoing it will be seen from Fig. I that the laminated brushes 56, 57 first leave the contacts 38, 39 so that the arcs may be taken, as already explained, by the carbon blocks 60 and 61, which are flanked throughout their movement by the U shaped blow-out magnets 43, 44.

For the purpose of tripping the trigger latch to effect delayed opening of the breaker incident to the persistence of a light abnormal condition of the circuit, I have provided a bimetallic thermic element 92 which is separately detailed in Fig. XIII, and which is shown in the form of a centrally slit bowed tongue. The ends 93, 94 of the thermic element 92 are pierced for the projection therethrough of the screw bolts 33 and 34 previously referred to. From Fig. IV it will be observed that the end 93 of the thermic element is in metallic contact with a washer 95 interposed between it and a plate 96 immediately beneath the nuts 36, 37 respectively on the screw bolts 33, 34, but insulated from the contact member 39

by an interposed fiber washer 97 and bushing 98. The other end of the thermic element 92 is, on the other hand, engaged between an insulating washer 99 and a metallic spacing washer 100. The element 92, the insulating washer 99 and the spacing washer 100 are interposed between the plate 96 and the contact 39 respectively. A fiber bushing 101 serves, in conjunction with the fiber washer 99, to insulate the end 94 of the thermic element 92 from the contact 39 as well as from the screw bolt 34. The flow of the electric current through the thermic element 92 is thus in the direction indicated by the arrows in Fig. IV, that is to say, from the terminal 25 and screw bolts 33, 34, through the metallic plate 96, and metallic spacing washer 95, then upward through the end 93 then downward through the end 94 and finally to the contact 39 by way of the metallic spacing washer 100. Thus, with the persistence of a slight abnormal circuit condition, the thermic element 92 is gradually heated, and in expanding exerts a force upward which oscillates or trips the trigger latch 78, whereby the bridging element is released to the action of the spring 77 and withdrawn from engagement with the contacts 38 and 39 to open the circuit through the breaker.

For manually opening and closing the circuit breaker I have devised means including a finger lever 102 which is mounted for rocking movement about the pin 72 as a bearing, the pin 72 connects the ends of the guides 65, 66. As shown in Fig. III, the actuating lever 102 comprises a metallic yoke 103 whereof the angularly directed extremities 104 are pierced to engage over the ends of the pin 72. The transverse bar or yoke 103 is rigidly embedded in a crescent shaped head 105 molded from dielectric composition with an apertured grasp projection 106. As shown in Fig. I, the outer curvature of the head 105 of the actuating lever is concentric with the axis of the fulcrum pin 72 to swing within an opening 107 in the front wall of the casing component 17. The inner side walls 105A of the head 105 of the actuating lever 102 contact with opposite sides of the guides 65, 66 which operate as stops to limit the extent through which said lever may be swung. As further shown in Figs. I and III, the extremities 104 of the yoke 103 of the actuating lever 102 have pivotally connected to them at 108, links 109 which in turn are pivotally connected at their opposite ends to the pin 86 of the slide block 87 carrying the trigger latch 78.

Together with the extremities 104 of the yoke 103, the links 109 function as a toggle connection between the trigger latch slide block 87 and the actuating lever 102, whereof the pivots 108 are normally above center with the circuit breaker closed as in Fig. I. Springs 110 tend to swing the actuating lever 102 upward about the pin 72 to "off" position, but the effect of these springs is overcome by the stronger spring 77 which operates to maintain the toggle connections 104, 109 cocked. However, upon tripping of the trigger latch 78 with the attendant elimination of the effect of the spring 77 as a factor, the actuating lever is swung upward to "off" position by the weaker springs 110, whereby the toggle connections 104, 109 are upset and the slide block 87 is automatically moved forward for reengagement of the hooks 80 of the trigger latch with the rollers 74 on the pin 73 of the bridging element slide 49. Such re-engagement of the hooks is facilitated through cooperation, with the rollers

74, of the sloping cam edges 111 of the hooks 80, and under the yielding action of the spring 87a, which latter influences the trigger latch 78.

A noteworthy feature of the operating arrangement which has been just described, is that it is incapable of preventing automatic opening of the breaker by abnormal circuit conditions, notwithstanding holding of the actuating lever 102 in the down or "on" position. Due to the fact 10 that, as shown in Fig. 1, the actuating lever 106 and consequently the bridge may be manually moved slowly to the open position. I prefer the modification shown in Fig. XIV in which the actuating lever 102a (similar in shape to 102) 15 has a U shaped lever 103a embedded rigidly in it, which trunnions on pin 72. The operating lever 112 is U shaped with a cross yoke 113 which acts as a stop on the brackets 65, 66. Links 109a are the same as 109, heretofore described. The 20 lever 112 has extensions 114, and also trunnions as a whole on the bearing pin 72. In the act of closing, the detent of the actuating lever, presses against the yoke 113 to move the lever 112 and links 109a to the closed passed dead 25 center position. In the act of manually opening the actuating lever 102a is free to move around on the bearing pin 72 until almost in the full open position, when the portion 105 presses against the projections 114 and gives it an initial 30 start to break the toggle action of 112 and 109a. Thus the main spring pulls the bridge to the open circuit position, with a quick and rapid action. Spring 110 of Fig. XIV performs similar as in Fig. I.

35 It will be noted that instead of the "trigger latching" mechanism shown in Fig. 1 and applying thereto, a "triple toggle latching" mechanism may be substituted, as shown in Fig. XV. Also ferrule terminals are readily substituted instead 40 of the knife blade terminals, as shown in Fig. XV, which is otherwise similar to Fig. I. The actuating lever 121 is similar to 102 except the yoke extremities 122 are positioned inside the uprights and pivotally attached to a link formed member 45 123, having a cross yoke 124 which acts as a stop to limit its dead center relationship in connection with the parallel link structure 125. The link structure 125 pivots to 123 at 126 and also to the bridge element at 127. The bridge element 50 is otherwise similar to bridge element 40. The bushings 128 and 129 provide a spaced relation for the link structure 125. An insulating cylinder 130 is riveted to the link structure as shown and is pressed clockwise by the bi-metallic strip 92 on 55 a small abnormal circuit condition to break the toggle alignment of the member 123 and the link structure 125 which allows the bridge element to be pulled to open circuit position by the spring 132, regardless as to whether the operating lever 60 121 is manually held or not. The armature 88 strikes the projection 131 of the link structure for a similar purpose as hereinbefore described upon large abnormal circuit conditions. It will be noted that the spring 132 has a similar function as spring 77.

65 Each of the ferrule terminals 133 consists of a counterbored cylinder of conducting metal, and each terminal is held to the base component by a bolt and a nut as shown in Fig. 1. The contact pieces, blow out magnets, contact brushes, etc., are substantially the same as those shown in Fig. 1.

70 Specific characteristics and claims of the "trigger" and "toggle" latching mechanisms appear

in my Patent No. 1,887,274, granted November 8, 1932.

Having thus described my invention, I claim:

1. In a circuit breaker, a movable bridging element, restraining means for the movable bridging element, an open circuit magnet enveloping the bridging element, an actuating lever pivoted to the magnet for manual operation of the circuit breaker, and a movable armature to complete the magnetic circuit upon abnormal circuit conditions in the movable bridging element to release the restraining means. 80

15 2. As an article of manufacture, a circuit breaker and switching device enclosed in a hollow casing of dielectric material, vertically aligned recesses external to the casing, terminals secured in said recesses, said terminals being adapted to engage fuse clips or the like, spaced contacts within the casing electrically connected to said terminals, a movable bridging element within the casing for making and breaking electrical connection between said contacts, a substantially U shaped magnet enveloping the bridging element, an operating lever pivoted to the said magnet for reciprocally moving the bridging 95 element substantially at right angles to the terminals, restraining means for the bridging element, and an armature for attraction to the magnet legs to release the restraining means, upon abnormal circuit conditions in the bridging element. 100

20 3. In a circuit breaker having spaced contacts, bridging mechanism including a movable bridging element for making and breaking an electrical connection between said contacts, a substantially U shaped magnet enveloping the bridging element, means for restraining the bridging element in closed circuit position, an actuating lever pivoted to the said magnet for manually opening and closing the bridging element, and an armature pivoted between the open legs of 110 said magnet to release the restraining means upon the occurrence of abnormal circuit conditions. 115

25 4. In a circuit breaker having spaced contacts, bridging mechanism including a movable bridging element for making and breaking an electrical connection between said contacts, a substantially U shaped magnet enveloping the bridging element, means for restraining the bridging element in closed circuit position, an actuating lever pivoted to the said magnet for manually opening and closing the bridging element, and an armature pivoted between the open legs of said magnet to release the restraining means upon the occurrence of abnormal circuit conditions, and a 120 thermic element connected to one contact and adapted to release the restraining means upon the occurrence of continuous abnormal circuit conditions. 125

30 5. In a circuit breaker, a movable bridging element, means for restraining movable bridging element, an open circuit magnet enveloping the bridging element, an actuating lever pivotally mounted upon the magnet for manually operating the circuit breaker, and a movable armature connected in the open magnetic circuit and upon abnormal circuit conditions in the movable bridging element said armature moves to release the restraining means. 130

35 6. In a circuit breaker having terminal contacts; a bridging element cooperative with the contacts; means for normally holding the bridging element in closed circuit position; an armature associated with the means for normally 140

135

140

145

150

- holding the bridging element in closed circuit position; and an open circuit magnet for guiding the bridging element in its movement toward and away from the contacts and capable, upon sudden 5 abnormal circuit condition of attracting the armature to effect tripping of the means for holding the bridging element in closed circuit position in order to open the circuit.
7. In a circuit breaker having in combination 10 spaced contacts, a bridging member cooperative with said contacts, means for manually operating said bridging member, a latch for holding the bridging members against the said contacts in a closed circuit position, means for guiding 15 the bridging member and latch in a direction substantially at right angles to the alignment of the spaced contact, means tending to withdraw the bridging member from closed circuit position, means to actuate the latch upon the occurrence 20 of abnormal circuit conditions, and an actuating lever whereby the breaker may be manually operated, said lever having lost motion only when said lever is in closed circuit position
- whereby it may be moved a fractional part of a revolution without having any action on the means for manually operating the bridging member.
8. In a circuit breaker, spaced contacts, a 80 bridging member cooperative with said contacts, means for actuating said bridging member, a latch for holding the bridging member against the said contacts in a closed circuit position, toggle connections coordinated with the latch, 85 means for guiding the bridging element and latch in a direction substantially at right angles to the alignment of the spaced contact, means tending to withdraw the bridging member from closed circuit position, means to actuate the latch upon the occurrence 90 of abnormal circuit conditions, an actuating lever whereby the bridging member may be manually operated, said lever having lost motion only when the lever is in closed circuit position whereby the lever will have limited free movement prior to having any action on the means for actuating said bridging member. 95
